UNITED STATES PATENT OFFICE.

FRANK A. GILCREST, OF PASADENA, CALIFORNIA.

INSULATING MEDIUM.

1,371,753.

Specification of Letters Patent. Patented Mar. 15, 1921.

Application filed July 25, 1919. Serial No. 318,241.

To all whom it may concern:

Be it known that I, FRANK A. GILCREST, a citizen of the United States, residing at Pasadena, in the county of Los Angeles and State of California, have invented certain new and useful Improvements in Insulating Mediums; and I do hereby declare the following to be a full, clear, and exact description of the invention, such as will enable others skilled in the art to which it appertains to make and use the same.

This invention relates to improvements in heat insulating or non-conducting medium, and more particularly to such as is adapted to assume a variety of forms and contours according to the particular use to which it is to be put.

The object in view is the provision of an efficient heat insulator or non-conductor inexpensive and easily produced and susceptible of adaptation to practically every possible use for heat insulating purposes.

With this and further objects in view as will in part hereinafter become apparent and in part be stated, the invention comprises certain novel constructions, combinations and arrangements of parts as subsequently specified and claimed.

In the accompanying drawing,—

Figure 1 is a sectional view through a sheet or slab of insulating material embodying the features of the present invention.

Figs. 2, 3 and 4 are similar views of slightly modified embodiments of the same.

Fig. 5 is an exaggerated fragmentary section of a part of the structure seen in Fig. 1.

Fig. 6 is a plan view on an exaggerated scale of a part of the structure seen in Fig. 4.

Referring to the drawing by numerals, 1 indicates a sheet, plate or slab made up of infusorial earth, preferably diatomite, and bonding fiber. The fiber, as shown and preferred, consists of strips of fabric, 2, 2, 45 embedded within the body of earth but is capable of a wide range of variation both as to the character of the fiber and its relative location. The fiber is preferably in the form of woven fabric as seen in Figs. 5 and 6, 50 with the earth so thoroughly worked into the interstices of the fabric as to be thoroughly bonded with the fabric.

In the construction of the sheet 2 diatomaceous earth in its natural state is first dried and then pulverized. The resulting powder is moistened with water and trituated

rated sufficiently to make a plastic paste. A layer of the paste is spread upon an appropriate support and pieces of fabric are laid on the surface of the paste either in contact or spaced apart and another layer of paste is placed on the fabric. At this point, the sheet building may be discontinued if the sheet is to be relatively thin, and in such instance it is preferable to have the fabric continuous as indicated at 2' in Fig. 2. Assuming that a greater thickness of the sheet or plate 1 is desired, additional pieces of fabric are placed on the new plastic layer and are preferably arranged to overlap the planes of the edges of the first pieces of fabric and a third layer of the paste is placed on the new layer of fabric. This building up process may continue until the plate becomes in fact a block of any desired thickness. In applying the fabric to the plastic mass or in applying the plastic mass to the fabric, the mass is subjected to the pressure of the instrument in the hand of the operator or other pressure or otherwise worked for forcing the particles of the earth into the interstices of the fabric so as to insure an effective bonding action, such as is indicated in the fragmentary showing in Fig. 5. While Fig. 5 is in fact a section taken from the structure seen in Fig. 1, it also accurately depicts a microscopic enlargement of any insulator embodying the features of the present invention in which infusorial earth has its particles forced into and through the interstices of the fabric with which it is bonded.

Fig. 5 is an exaggerated fragmentary section of a part of the structure seen in Fig. 1. Fig. 6 is a plan view on an exaggerated scale of a part of the structure seen in Fig. 4. Referring to the drawing by numerals, 1 indicates a sheet, plate or slab made up of infusorial earth, preferably diatomite, and bonding fiber. The fiber, as shown and preferred, consists of strips of fabric, 2, 2, 45 embedded within the body of earth but is capable of a wide range of variation both as to the character of the fiber and its relative location. The fiber is preferably in the form of woven fabric as seen in Figs. 5 and 6, 50 with the earth so thoroughly worked into the interstices of the fabric as to be thoroughly bonded with the fabric.

In each instance when the insulating medium is completed, whether in the form of a thin sheet or thick plate or block, the medium is dried out preferably by the natural heat of the atmosphere, as, for example, by being left exposed in the Arizona desert or elsewhere where the atmosphere is quite dry. It is preferable to effect the drying operation while protecting the insulator from the first action of the sun's rays so as to avoid baking.

The uses to which this improved insulating medium is adapted are very numerous, including use for coverings, wall linings, refrigerator linings, pipe covering, and practically everywhere where heat is to be excluded or retained.

The diatomaceous earth is so effective as an insulator that when reduced to a powder and then treated in the manner described to 10 produce a blanket for bed covering, I find the product possesses so little weight as to be particularly comfortable and especially pleasing in use. The finished covering possesses ample flexibility to conform to the 15 contour of the body after the manner of ordinary wool blankets, while the adhesion

of the particles in their bonded relation to the fabric and the cohesion of the particles with respect to themselves insure durability of the product as well as sanitation in its 20 use.

What I claim is:—

Heat insulating medium comprising a fabric and pulverized diatomaceous earth applied to the fabric and worked into the interstices thereof while in a plastic condition.

In testimony whereof I affix my signature in presence of two witnesses.

FRANK A. GILCREST.
